UNITED STATES PATENT OFFICE.

GERTRUDE E. GROOM, OF WALTHAM, MASSACHUSETTS.

DOLL.

Application filed December 7, 1921. Serial No. 520,527.

To all whom it may concern:

Be it known that I, GERTRUDE E. GROOM, a citizen of the United States, residing at Waltham, county of Middlesex, State of Massachusetts, have invented a certain new and useful Improvement in Dolls, of which the following is a specification, reference being had therein to the accompanying drawings.

The invention relates to a new and useful improvement in dolls. The object of the invention is to produce a toy doll or animal which is especially adapted for use by babies and very young children. The special object of the invention is to produce such a doll that is not easily broken and is composed entirely of soft material so that the child cannot possibly be injured by any hard or sharp portions of the article; also to produce a doll which can be very easily, simply and economically made, and which is complete in itself without requiring clothes of any kind made separate therefrom, and yet which has the appearance of a fully dressed doll.

The invention consists substantially in making the doll of pieces of woolly faced material cut to the shape of a head and body, placing two similar pieces back to back, that is, with the skin side of one in contact with the skin side of the other, and fastening them together at the edges.

The invention will be fully understood from the following description when taken in connection with the accompanying drawings, and the novel features thereof will be pointed out and clearly defined in the claims at the close of this specification.

In the drawings, Fig. 1 is a front elevation of a two-faced doll embodying the invention.

Fig. 2 is a side elevation of the doll shown in Fig. 1.

Fig. 3 is a plan view.

Fig. 4 is a plan view of a blank such as used for making the body.

Fig. 5 is an end view of the blank shown in Fig. 4.

Fig. 6 is a plan view of a blank used for making one of the arms.

Fig. 7 is a side elevation of a one face doll.

Fig. 8 is a plan view of a sole out of which the body and arm blanks may be formed.

Referring now to the drawings, there are

first provided two blanks A, B, for the body portions of woolly faced material, preferably sheep skin, which are cut out in pairs, each member having the leather or skin back 1 with the wool facing 2 after the ordinary manner of so-called sheep's skin or lamb's wool, such as used for soles of lamb's wool slippers. Each of these is cut to the form of the full body length, including the head, trunk, and lower portion, as shown in the drawings. Preferably the lower portion is not cut out to the form of legs but is shaped as shown to represent a fully dressed child, so that the legs and feet do not show. If preferred, however, the blanks may be cut more in detail to show the feet and legs.

The said two members are then placed back to back, that is, skin to skin, with the woolly side out and secured together around their edges, preferably by stitches 3. The arms 4—4 are made also of similar woolly material by taking a blank piece such as shown at C in Fig. 6, and folding it over upon itself, along the dotted line 8 and sewing it at its edges, as shown at 5, and attaching this to the two body members by stitching as shown at 6.

The doll is thus made complete as shown in Figures 1 and 2 having a thick woolly surface on both sides.

Each arm is preferably made of a single piece folded over upon itself so that there is a seam only on one edge. Preferably for this purpose a single blank C is cut out of a piece of sheep skin which is then folded along its median line 8 and sewed together along the two edges.

Suitable eyes, nose and mouth may be marked on the two opposite face sides. In the form shown in the drawings, there is a depression 7 formed on each face side by pressing it in and small buttons are attached to represent the eyes, while the mouth and nose are formed by thread. It is obvious, however, that these features may be produced in any way, either with materials attached thereto, to represent the features or by marking the features out with any suitable marking tool.

In the preferred form there is represented a face on both sides so that it will appear like a two-faced doll. If preferred, however, there may be produced a face only on one side while the opposite side will represent the back of the head, as shown in Figure 7.

- The blanks for making the doll may all be cut out of a large sheet of sheep skin, each blank to be made of suitable shape and size. A very convenient and easy method 5 of making them, however, is to take a pair of ordinary lamb's wool soles, such as are used for making boudoir slippers and cutting off the toe portion of each one, as shown by the dotted line 9 in Figure 8. 10 Each toe portion which has been cut off is adapted for forming a single arm by folding it in the manner already described. 15 The finished doll has a thick, soft woolly exterior throughout except at the seamed edges. It is soft, and flexible and unbreakable by falling or being thrown on the floor, and has no part by which a small child can be hurt or injured in any way by handling it. It is also washable. 20 While I have described the doll as preferably made of lamb or sheep skin with the natural wool unremoved, there might be employed imitation sheep skin with a woolly bat thereon which could be utilized to make 25 a cheaper doll embodying the invention. It is obvious that the arms may be integral with the body instead of being made in separate pieces from the body and then attached thereto. 30 While the form of article shown in the drawings is a representation of a doll, it is obvious that the invention is adapted for application in the manufacture of toy animals, or any article in similitude of a living creature. In such case the only difference 35 in method of construction from that shown in the drawings would be simply in the contour of the blanks which form the front, back and limbs of the animal. 40 What I claim is:
1. An unstuffed doll having a head and body portion composed of a pair of mated blanks of unshorn sheepskin, each shaped

to the contour of the head and body of a doll and superimposed upon each other with the 45 woolly faces outside and the flesh sides of the two skins lying flat against each other and secured together at their edges.

2. An unstuffed doll having a head and body portion composed of a pair of mated 50 blanks of unshorn sheepskin, each shaped to the contour of the head and body of a doll and superimposed upon each other with the flesh sides of the two skins lying flat against each other and secured together at their 55 edges, and arms each formed of a piece of sheepskin folded with the woolly side out and secured to the sides of the body portion.

3. An unstuffed doll having a head and body portion composed of a pair of mated 60 blanks of unshorn sheepskin, each shaped to the contour of the head and body of a doll and superimposed upon each other with the flesh sides of the two skins flat against each other and secured together at their edges, 65 and arms each formed of a piece of sheepskin folded with the woolly side out and secured to the sides of the body portion, the head portion having a depressed face portion with features delineated thereon. 70

4. An unstuffed doll having a head and body portion composed of a pair of mated blanks of unshorn sheepskin, each shaped to the contour of the head and body of a doll superimposed upon each other with the flesh 75 sides of the two skins facing each other and secured together at their edges, and arms each formed of a piece of sheepskin folded with the woolly side out and secured to the sides of the body portion, the front and back 80 of the head portion each having a depression shaped to form a face and having features delineated thereon.

In testimony whereof I affix my signature.

GERTRUDE E. GROOM.
